PROCESS OF AND APPARATUS FOR DISTILLING HYDROCARBONS UNDER PRESSURE.

Application filed June 7, 1922. Serial No. 566,470.

My invention relates to an improved process of and apparatus for distilling oils under pressure, involving an operation commonly known as "cracking" by which a greater volume of lower boiling point hydrocarbons is produced than is obtainable by ordinary methods of distillation. The successful cracking of oils under pressure involves two major problems; and the degree to which these two problems are solved determines the efficiency and economy of the process itself. The first of these problems is to efficiently and economically crack a portion of the oil; and the second is to effect a clean separation of the portion cracked and the portion that will not crack at the operating temperature and pressure.

In the solution of the first problem it is essential to avoid local overheating in order to prevent excessive coke formations which constitute the greatest obstacle and hindrance in all known cracking systems of oil distillation. The prevention, or at least the substantial reduction, of coke formation is, in my present invention, brought about partly by effecting an exchange of heat from the distillate produced and the residuum drawn off to the crude material so that the additional heat required of the primary heating medium is reduced to a minimum, thereby avoiding local overheating; and partly by employing a heating system that causes the crude material to be heated in a progression, whereby the heating strain is so reduced and distributed and the intensity of the heat required is so lowered that only a negligible amount of coke is produced. Furthermore, in my present apparatus practically all of the carbon or coke that is generated in the apparatus is deposited on the surfaces of certain heating plates in the boiler or still over which the crude material flows in the form of a wide thin film, washing the carbon or coke off practically as fast as it is deposited. Moreover the boiler or still is of such a construction as to render the heating plates easily accessible for cleaning when required.

In carrying out my invention, I pass the vapor given off from the boiler or still first through a dephlegmator, and thence through a vapor condenser. In the dephlegmator and condenser the reflux and vapor impart their latent heat of vaporization to the incoming oil, which latter travels counter-current to the flow of the vapor in both the

condenser and the dephlegmator, so that there is a gradual exchange of heat in regular progression from the vapor to the crude material; the condensed vapor or distillate first encountering the unheated oil, and the latter being progressively and uniformly heated up as it travels through the increasingly heated portions of the vapor condenser and dephlegmator. Not only does the inflowing oil thus absorb the heat of the vapors in the manner described, but it likewise absorbs heat from the residuum of the still which is caused to flow, under the pressure maintained in the system, through the dephlegmator and vapor condenser in the same direction as the vapor counter-current to the flow of the incoming oil. Finally, the reflux from the dephlegmator joins and commingles with the incoming oil after the latter has passed through the condenser and dephlegmator, and passes back into the still preferably through the same pipe by which the distilled vapor travels from the still to the dephlegmator, thereby absorbing a still further amount of heat from the vapor.

In the accompanying drawings I have illustrated a complete apparatus capable of carrying out my improved process of oil cracking and embodying in a practical and preferred form the novel structural features of my present invention; and referring thereto—

Fig. 1 is an elevation, partly in vertical section, illustrating a complete plan or system embodying my invention:

Fig. 2 is an enlarged vertical section through the still;

Fig. 3 is an enlarged vertical section through the dephlegmator and condenser and their immediately associated parts and connections;

Fig. 4 is a further enlarged vertical section through one of the vapor tubes or conduits of the dephlegmator, illustrating a structure by which a spiral or serpentine upward flow of the vapor and backward flow of the reflux is effected;

Fig. 5 is a cross section on the line 5—5 of Fig. 4;

Fig. 6 is an enlarged horizontal section through the still taken on the line 6—6 of Fig. 2;

Fig. 7 is an enlarged cross section through a pair of heating plates taken on the line 7—7 of Fig. 2;

Fig. 8 is an enlarged cross section through the dephlegmator and vapor condenser taken on the line 8-8 of Fig. 3;

Fig. 9 is a vertical section of a device for fixing the level of the condensate in the condenser; and

Fig. 10 is an enlarged cross-section on the line 10-10 of Fig. 9.

I will first briefly describe the principal units of the complete system and their connections, and I will then describe in detail the several units themselves.

Referring to Fig. 1, R designates a residuum tank of ample capacity and mounted on a suitable foundation, said tank being capable of sustaining an internal pressure of anywhere from one to one thousand pounds per square inch gauge pressure. On this tank is mounted the boiler or still designated as an entirety by S. From the top of the still coaxially disposed pipes 10 and 11 lead into the bottom of a dephlegmator and scrubber designated as an entirety by D. From the upper end of the dephlegmator coaxially disposed outer and inner pipes 12 and 13 lead into the upper end of a vapor condenser designated as an entirety by C. 14 designates a pipe through which the crude material enters the system, this pipe entering the intermediate or oil chamber of the vapor condenser. From the upper portion of this latter a pipe 15 conducts the oil into the top of an oil tank T, equipped with a float valve 99 from the lower end of which tank a pipe 16 carries the oil into the dephlegmator D. From the bottom of the condenser C pipes 17 and 18 convey the condensed distillate into a receiving drum Z from the upper end of which the permanent gas is released through a pipe 19 and cock 20, and from the lower end of which the distillate flows to storage through a pipe 21 and cock 22.

The still.

The boiler or still is mainly illustrated as to its structural details in Figs. 2, 6 and 7. 23 designates the lower head of a cylindrical metal tank constituting the housing or shell of the vapor generator. This tank head 23 may conveniently be mounted and supported directly on the residuum tank R by suitable feet 24, and communicates with said tank by a central tube 25 through which the residuum flows from the bottom of the still directly into the residuum tank. Mounted on the tank head 23 are a pair of parallel upright frame structures designated as an entirety by 26, which constitute supports for a pair of generally W-shaped groups (left and right) of hollow heating plates joined at their convergent ends by hollow headers and internested so as to form between adjacent plates of the two groups a continuous zigzag conduit for the gravity flow of the crude material in a broad thin

continuous film or stream from top to bottom. In Fig. 2 I have designated the left hand group as an entirety by 1 and the right hand group which interfits therewith as an entirety by 2. The heating plates of both groups are structurally identical and are best shown in detail in the cross sectional views, Figs. 6 and 7, wherein 27 designates a group of tubes disposed side by side at equally spaced intervals, and 28 designates each of a pair of longitudinally corrugated boiler plates which overlie and underlie respectively the tubes 27, and 29 designates rivets uniting the two plates midway between adjacent tubes 27. By this construction is formed a hollow heating plate structure which provides two separate groups of conduits for heating media, namely, the interiors of the tubes 27, and the passages formed between adjacent tubes 27 and the plate sections spanning adjacent tubes. Figs. 2 and 6 show one practical means of uniting the convergent ends of each connected pair of heating plates so as to render the internal conduits of said plates continuous. 30 designates a hollow header or manifold that extends transversely of the inner convergent ends of the heating plates and is provided with a central longitudinal partition or bridge plate 31 extending from end to end thereof, and is further provided with a tapped cleanout holes 32 in its outer wall normally closed by plugs 33. By reference to Fig. 6 it will be observed that the header 30 carries trunnions 34 journaled in the frame uprights 26. The tubes 27 are extended through the inner wall of the header and are fitted into the partition wall 31, whereby said tubes communicate freely with a header chamber 30^a on the outer side of the partition wall. The inner wall of the header 30 is formed with apertures 35 at points between adjacent tubes 27, thus throwing the heating plate conduits that lie between adjacent tubes 27 into communication with a header chamber 30^b on the inner side of the partition 31.

The outer convergent ends of adjacent heater plates are placed in communication with each other by a generally similar header construction, comprising individual headers or manifolds 30' structurally identical with the headers or manifolds 30, and having their respective inner and outer chambers connected by vertical tubes 36 and 37. As shown in Fig. 6, the headers 30' have at their ends trunnions 38, similar to the trunnions 34 of the headers 30, which trunnions 38 are likewise mounted and supported in the upright frame 26.

The above described structure affords a continuous zigzag multiple tube conduit for the upward flow of a heating agent through the heating plate tubes 27, the header compartments 30^a, and the pipes 37, and another continuous multiple tube zigzag conduit for

the upward flow of another heating medium through the passages formed by and between the tubes and the boiler plates, the header compartments 30^b, and the pipes 36.

5 In preferred practice the last mentioned multiple tube conduits are used for the upward flow of the primary heating medium, which is preferably superheated steam, while the first mentioned group of conduits is employed for the upward flow of residuum from the residuum tank R. To insure the downward and forward flow of the crude material, the longitudinal edges of each plate which forms a part of the trackway 10 or path of the material are turned upwardly, as shown at 39 in Fig. 7 to a level slightly above the height of the headers, thus preventing lateral spilling or overflow of the crude material, and insuring its continuous 15 downward flow in a zigzag direction over the header at the foot of the plate down onto the next underlying heating plate.

20 The apparatus last described, consisting of the internested generally W-shaped hollow heating plates with their connecting headers and pipes, is substantially identical with that shown, described and claimed in a former application filed by me on the 29th day of April 1922, Serial No. 557,421, and 25 no claim thereto specifically is made herein.

Surrounding and completely enclosing the vapor generating apparatus last described is a cylindrical tank or bell, comprising a tank body 46 and an upper tank head 41 which may be integral or continuous with the body 40, and is so shown herein. The lower tank head 23 and the tank body 40 have mating flanges 23' and 40' (Fig. 2) providing a packed tongue and groove joint 30 at 42 and united by bolts or rivets 43. The still housing or tank is, of course, constructed of a material capable of withstanding the maximum internal pressure under which the system may be operated and which I contemplate may approximate in some instances one thousand pounds per square inch.

35 From the outer chambers of the lowermost headers 30' of the two groups of heating plates there extend downwardly pipes 44 (Fig. 2) through the lower tank head 23 and the top of the residuum tank R, said pipes 44 terminating slightly above the bottom of the residuum tank, and serving to conduct residuum, under the internal pressure existing in the residuum tank, upwardly into the lower ends of the residuum conduits of the two groups of heating plates. From the corresponding topmost headers 30' 40 pipes 45 conduct the residuum through a vertical pipe 46 and coupling 47 into the residuum outflow pipe 11 previously mentioned.

45 designates a pipe for the inflow of superheated steam or other fluid primary heating medium, from which branch pipes 49

lead to the inner chambers of the two lowermost headers 30'; and from the corresponding chambers of the topmost headers 30' branch pipes 50 conduct the steam to a single steam discharge pipe 51 that is carried 50 through the head 41 of the still tank.

The said top 41 of the still tank has a central vapor outlet opening 52, through and over which is fitted a short pipe section 53 carrying a coupling or union 54, to which latter is connected the pipe 10 previously described as enclosing the residuum pipe 11.

55 Directly beneath the pipe section 53 is a funnel 55, through which the incoming crude material, together with the reflux, is delivered to and overflows the trough 56 extending crosswise of the topmost heating plate, by which the crude material overflows onto the latter.

The dephlegmator.

60 The detailed structure of the dephlegmator is shown mainly in Figs. 3 and 8. This comprises a cylindrical tank body 57 and lower and upper heads 58 and 59 joined to the tank body by tongue and groove joints as shown. This tank is divided by transverse tube sheets or diaphragms 58' and 59' into upper, intermediate and lower compartments 60, 61 and 62, respectively. Extending between and at their ends rolled into the diaphragms 58' and 59' are several circular groups of vapor tubes 63, through which the vapors from the still flow from the lower compartment 62 to the upper compartment 60. The vapor scrubbing and condensing effects of the tubes 63 may be enhanced by equipping each tube with a spiral 64, clearly shown in detail in Figs. 4 and 5, by which the vapor flowing upwardly through the tube is caused to follow a serpentine path.

65 Inwardly of the innermost group of vapor tubes is disposed a similar circular group of tubes 65 which constitute residuum conducting tubes. To the lower diaphragm 59' is secured a large tube section or manifold 66 that encircles and communicates with the lower ends of the residuum tubes 65; and the manifold 66 is connected by a pipe 67 and union coupling 68 with the residuum flow pipe 11 from the still; and the bottom 58 of the dephlegmator tank is connected by a pipe 69 and flanged and bolted coupling 70 with the pipe 10 leading from the top of the still.

70 Interposed in the pipe 10 is a flanged T-coupling 10^a from the upper side of which vapor conducting pipes 71 and 72 lead into the upper portion of the lower compartment 62 preferably at diametrically opposite points of the latter.

75 Fitted into and depending from the lower diaphragm 59' and communicating with the intermediate chamber 61 is a pipe 73 for the discharge of the crude material from the in-

termediate chamber 61 to the lowermost chamber 62; and in this pipe 73 is a regulating valve 74 having a stem 75 extending through a packed bearing in the cylindrical wall of the dephlegmator tank, by which the flow of the crude material can be regulated as hereinafter described.

Secured to the upper diaphragm 58' and encircling the upper ends of the residuum tubes 65 and communicating with the latter is a large pipe section or manifold 76, similar to the manifold 66; and extending laterally therefrom is the residuum delivery pipe 13, this latter passing through the vapor transfer pipe 12 that communicates with the topmost compartment 60.

Joined to the discharge pipe 16 leading from the overhead supply tank T by an elbow coupling 79 is a pipe 80 that extends centrally through the upper head 59 of the dephlegmator cylinder through the upper compartment 60 and its contained manifold 76, into and nearly to the bottom of the intermediate compartment 61. Preferably and as herein shown, the lower end of the pipe 80 is closed, and said pipe is provided with perforations or small apertures 81 that extend practically the full length of that portion of the pipe lying within the chamber 61 and allow the incoming oil to trickle through and build up in the space around the vapor and residuum tubes. In the upper end of the pipe 80 is a valve 82 having a stem 83 by which the amount of oil entering the perforated pipe 80 may be controlled at will.

The condenser.

From the dephlegmator last described the uncondensed portion of the vapors and the uncondensable gases flow through the pipe 12, and the residuum flows through the pipe 13, to the condenser C. Structurally the condenser is substantially a duplicate of the dephlegmator, omitting the perforated oil delivery pipe 80, with the vapors and residuum flowing from top to bottom, instead of in the reverse direction. Briefly describing the structure of the condenser, the same comprises a cylindrical tank body 84 and lower and upper heads 85 and 86 joined to the tank body by the tongue and groove joints shown. The tank is divided by transverse tube sheets or diaphragms 87 and 88 into upper, intermediate and lower compartments 89, 90 and 91, respectively. Extending between and at their ends rolled into the diaphragms 87 and 88 are several circular groups of vapor tubes 92, through which the uncondensed vapors and uncondensable gases from the dephlegmator flow from the upper compartment 89 to the lower compartment 91.

Inwardly of the innermost group of vapor tubes is disposed a group of tubes 93 which

constitute ducts for the downward flow of residuum. To the upper diaphragm is secured a large tube section or manifold 94 that encircles and communicates with the residuum tubes 93, and into which the residuum conducting pipe 13 is led. The vapor conducting pipe 12, which encircles the residuum pipe 13, is similarly connected into the side of the upper compartment 89.

Secured to the lower diaphragm 88 and encircling the lower ends of the residuum tubes 93 and communicating with the latter is a large pipe section or manifold 95, similar to the manifold 94; and from the bottom of the manifold 95 a residuum discharge pipe 96 leads through the lower head 85 of the condenser cylinder and thence to any suitable point of discharge or storage. In the pipe 96 is a flow regulating valve 97 (Fig. 1) having a stem 98 by which it may be manually manipulated.

From the lower end of the condenser tank the distillate passes by the pipes 17 and 18 into the receiving drum Z, as already described.

The pipe 14 through which the crude material enters the system leads into the intermediate compartment 90 substantially at the lower end of said compartment; and the incoming crude material completely fills said intermediate compartment surrounding and being heated by the vapor and residuum pipes, and from a point near the upper end of said compartment flows through the pipe 15 into the upper end of the tank T, the level in which latter is maintained constant by a float controlled valve 99 (Fig. 1).

In order to maintain a predetermined or desired level of the condensate in the condenser C the same is preferably equipped with a leveling device similar to that disclosed in my former application Serial No. 557,421, hereinabove referred to, and also disclosed and claimed in another application filed by me on the 29th day of December, 1921, Serial No. 525,597. Briefly describing the said leveling device, the vertical drain pipe 18 with which the horizontal drain pipe 17 communicates extends to a considerable height above the pipe 17 and opposite the condenser C. The pipe 18 is provided with a partition 100 slightly below the junction of the horizontal pipe 17, in which partition is slidably mounted a tube 101 having an open upper end, as shown in Fig. 10, carrying a spider 102, in the hub of which is swivelled the lower end of a screw-threaded rod 103, this latter extending upwardly through and in threaded engagement with a head or cap 104 on the upper end of the pipe 18 and equipped with a hand wheel 105 for turning the same. By raising and lowering the overflow tube 101, the upper open end of the latter establishes the level of the liquid in the condenser in an obvious manner.

The oil supply pipe 14 is equipped with a cock 106 and also with a check valve 107 adjacent to its connection to the condenser. For manipulating the valves 74 and 82 from the neighborhood of the valves 20, 22, 97 and 106, the former is provided with operating connections comprising miter gears 108, 109, rod 110, miter gears 111, 112 and rod 113; and the latter is provided with operating connections comprising miter gears 114, 115 rod 116, miter gears 117, 118, and rod 119.

In the operation of the system, the cock 106 being opened, the crude oil to be cracked is forced by a pump from an outside source through line 14 past check valve 107 into the intermediate chamber of condenser C filling the space around the tubes of the latter. Thence the oil continues upwardly through line 15 past float valve 99 into the overflow tank T, in which a constant level is maintained. From tank T the oil flows by gravity through pipe 16, and by manipulating valve 82 the amount entering the perforated pipe 80 is controlled at will. The perforations in said pipe allow the incoming oil to trickle therethrough and build up around the vapor and residuum tubes in the intermediate chamber, so that the coldest portion is on top and the hottest portion is at the bottom, with the body of oil moving from top to bottom counter-current to the upward travel of the vapors and residuum. From the bottom of the intermediate chamber of the dephlegmator the oil flows through pipe 73 into the bottom chamber 62 of the dephlegmator. With a constant flow entering through pipe 80, the height of oil in the intermediate chamber of the dephlegmator may be controlled at will by means of the regulating valve 74. This in turn determines the time required for the oil to pass through the chamber, or, in other words, the length of time it is in contact with the vapor and residuum tubes, which, in turn, controls the amount of reflux dropping out of the vapors. In the compartment 62 the feed oil mixes with the reflux from the vapors, and the mixture flows through the pipes 69, 10, and 53, and funnel 55 and overflow trough 56 onto the first heating plate. Flowing back and forth over the several heating plates, the reflux is again vaporized together with such portion of the crude oil as will vaporize at the operating temperature and pressure. From the bottom of the still the residuum flows through pipe 25 into tank R.

Since there is a wide range of temperature increase from the top heating plate to the bottom heating plate and the vapors released from the upper plates are forced to mingle in the same chamber with the vapors released from the bottom plates, the former are heated by the latter far above their vaporizing temperatures, which heating aids their cracking to the lower boiling points.

Bearing in mind that there is a complete set of boiling ranges of oil in the vapor state between the top and the bottom of the still, and that there has been a clean separation of vapor and residuum with the latter removed, and that constantly there is added to this mass of vapor the additional vapor from reflux that was previously partially cracked, an ideal condition to assist in cracking is presented. It should also be noted that this cracking zone is attended with a continued retrogression of temperature creating a continual scrubbing in an upward direction.

The residuum is forced upward from the tank R by the pressure maintained on the latter and, after passing through the residuum conduits of the heating plates, leaves the still through pipes 45, 46 and 11 which are enclosed within the vapor line. Thence the residuum follows a path within and parallel to the path of the vapors to the bottom of condenser C, and is lowered in temperature in the same manner as the vapors, namely, by giving up its heat to the inflowing oil traveling counter-current thereto.

The vapors from the still flow through the upper portion of pipe 10 and the branch pipes 71 and 72 into the bottom chamber 62 of the dephlegmator, whence they travel upwardly through the vapor tubes 63, following the circuitous paths created therein by the spirals; during which travel a portion of the vapors is condensed and drops backwardly into the chamber 62. By raising or lowering the level of the oil around the tubes through manipulation of the regulating valve 74, the amount of reflux dropping out of the vapors is increased or decreased. This controls the temperature of the vapors emitted from the dephlegmator, and this in turn determines the boiling range of the distillate produced.

The vapors traveling through line 12 over into the condenser continue downwardly through the tubes 92 of the condenser in which they are cooled and condensed by the crude oil traveling upwardly, with the aid of the leveling device which increases or decreases the condensed liquid level in the condenser. Flowing out of the bottom of the condenser through lines 17 and 18, the distillate continues downwardly into the receiving drum Z. From this latter the distillate is released as desired through valve 22 and line 21 to storage. The permanent gas that accompanies the distillate to the receiving drum is released through valve 20 and line 19 only fast enough to maintain a constant pressure in the system.

From the foregoing it will be seen that all of the heat in the distillate produced and residuum drawn off is transferred advantageously to the crude material. This latter at all times is traveling counter-current to the distillate and residuum and at

- all times is in close proximity to extract heat from both. Thus before the crude material reaches the still, and even to the time it drops out of the still as residuum, it is heated in a progression. This distributes the heating sufficiently to prevent local overheating at any point or points, so that a minimum of coke is produced. Most of the coke produced is washed into the residuum tank by the flow of the oil. Thus all fire hazards that are caused by local overheating with direct fire are entirely eliminated in the present system. Any coke deposited on and adhering to the upper surfaces of the heating plates of the still is easily removed by disconnecting the pipe lines at the top of the still and stripping the tank or bell off the stack of heating plates so that access to the latter is readily had.
- 20 The cracked vapors flow through a continuous passage that is constantly decreasing in temperature all the way from the bottom of the still to the top of the dephlegmator. This creates an ideal condition for cracked vapor to be further cracked in a continued decreasing temperature zone, with a long enough time interval elapsing for reactions and equilibrium to be set up. It is a well known fact in the art of cracking oil that it is not necessary to employ pressure to accomplish cracking. The heat alone does the cracking; but to attain desirable distillates it is advantageous to employ pressure as a retarding agent; that is, to hold the vapors in the cracking zone and reaction zones long enough for desirable compounds to form. The higher the pressure, the better the control, and the lower the boiling point of the distillate becomes. In addition, first it is desirable to heat in a progression in the cracking chamber, allowing the vapors to rise and diffuse in the cracking zone. In my still the hottest vapors are at the bottom and the coldest at the top. Therefore, diffusion of vapors takes place in a decreasing temperature zone. Secondly, in the reaction zone (dephlegmator) it is a distinct advantage for vapor to pass through a decreasing temperature zone. In my dephlegmator this condition exists, and as the vapors travel upward, the heavier portions are refluxed and drop down, creating a scrubbing effect. The vapor finally emitting from top of the dephlegmator is of a much higher temperature than the average boiling point of distillate produced. Thus it is correct to state that said vapors are in a condition of superheat, that is they are still much higher than their own boiling point. Therefore, cracking is taking place in the dephlegmator. Thirdly, it is quite essential that a long enough time elapse from the time the oil is vaporized in the bottom of the still to the time it reaches the top of the reaction chamber (dephlegmator) for cracking reaction, and equilibrium to be set up, or the distillate produced will be undesirable; that is, it will contain too large a percent of unsaturated compounds and will not be of the proper boiling range.
- Finally, the apparatus is well adapted to serve as a continuously operating unit, thereby decreasing the strain on material that is always present where a cracking system operates in cycles with batch runs.
- I claim—
1. A process of distilling hydrocarbons under pressure to produce lower boiling point hydrocarbons, which consists in passing the crude material through a still, subjecting the same in said still to the heat of a fluid heating medium and residuum out of contact with both of the latter, said heating medium and residuum being maintained out of contact with each other, passing the vapors and residuum from said still into a dephlegmator out of contact with each other, returning the reflux from said dephlegmator to said still, and passing the uncondensed vapors from said dephlegmator to a condenser. 80
2. A process of distilling hydrocarbons under pressure to produce lower boiling point hydrocarbons, which consists in passing the crude material successively through a vapor condenser, a dephlegmator and a still, simultaneously passing the residuum from said still through the dephlegmator counter-current to the flow of the crude material and out of contact with the latter, passing the vapors generated in said still into said dephlegmator, and passing the uncondensed vapors from said dephlegmator to said condenser. 95
3. A process of distilling hydrocarbons under pressure to produce lower boiling point hydrocarbons, which consists in passing the crude material successively through a vapor condenser, a dephlegmator and a still, simultaneously passing the residuum from said still through the dephlegmator and the condenser counter-current to the flow of the crude material and out of contact with the latter, passing the vapors generated in said still into said dephlegmator, and passing the uncondensed vapors from said dephlegmator to said condenser. 105
4. A process of distilling hydrocarbons under pressure to produce lower boiling point hydrocarbons, which consists in passing the crude material successively through a vapor condenser, a dephlegmator, and a still, simultaneously passing the residuum from said still through the latter, the dephlegmator and the condenser counter-current to the flow of the crude material and out of contact with the latter, passing the vapors generated in said still into said dephlegmator, and passing the uncondensed vapors from said dephlegmator to said condenser. 120
- 125
- 130

5. A process of distilling petroleum hydrocarbons under pressure to produce lower boiling point hydrocarbons, which consists in passing the crude material in a continuous flow successively through a vapor condenser, a dephlegmator and a still, simultaneously passing the residuum from said still through the latter, the dephlegmator and the condenser counter-current to the flow of the crude material and out of contact with the latter, regulating the volume of crude material in the dephlegmator to produce distillates of the desired boiling point, passing the vapors generated in said still into said dephlegmator, passing the uncondensed vapors from said dephlegmator to said condenser, and commingling the reflux from the dephlegmator with the crude material flowing from the latter into the still.
6. A process of distilling hydrocarbons under pressure to produce lower boiling point hydrocarbons, which consists in passing the crude material successively through a vapor condenser, a dephlegmator and a still, simultaneously passing the residuum from said still through the latter, the dephlegmator and the condenser counter-current to the flow of the crude material and out of contact with the latter, passing the vapors generated in said still into said dephlegmator, passing the uncondensed vapors from said dephlegmator to said condenser, controlling the volume of liquid condensate in said condenser to thereby regulate the amount of heat transferred to the crude material and commingling the reflux from the dephlegmator with the crude material flowing from the latter into the still.
7. A process of distilling hydrocarbons under pressure to produce lower boiling point hydrocarbons, which consists in passing the crude material successively through a vapor condenser, a dephlegmator and a still, simultaneously passing the residuum from said still through the latter, the dephlegmator and the condenser counter-current to the flow of the crude material and out of contact with the latter, passing the vapors generated in said still into said dephlegmator, passing the uncondensed vapors from said dephlegmator to said condenser, controlling the volume of liquid condensate in said condenser to thereby regulate the amount of heat transferred to the crude material, regulating the volume of crude material in the dephlegmator to produce distillates of the desired boiling point, and commingling the reflux from the dephlegmator with the crude material flowing from the latter into the still.
8. In an oil cracking system of hydrocarbon distillation, the combination of a still, a dephlegmator provided with conduits for the separate flow of vapors and residuum therethrough in one direction and of crude material therethrough in the opposite direction, means for passing residuum from said still to the residuum conduit of said dephlegmator, means for passing the vapors from said still to the vapor conduit of said dephlegmator, and means for passing the crude material and reflux from said dephlegmator to said still.
9. In an oil cracking system of hydrocarbon distillation, the combination of a still, a dephlegmator provided with conduits for the separate flow of vapors and residuum therethrough in one direction and of crude material therethrough in the opposite direction, a pipe for conducting residuum from said still to the residuum conduit of said dephlegmator, and a pipe constituting a conduit for the vapor from the still to the dephlegmator and for the crude material and reflux from the dephlegmator to the still.
10. In an oil cracking system of hydrocarbon distillation, the combination of a still, a dephlegmator provided with conduits for the separate flow of vapors and residuum therethrough in one direction and of crude material therethrough in the opposite direction, a pipe for conducting residuum from said still to the residuum conduit of said dephlegmator, and a pipe surrounding said residuum pipe and constituting a conduit for the vapor from the still to the dephlegmator and for the crude material and reflux from the dephlegmator to the still.
11. In an oil cracking system of hydrocarbon distillation, the combination of a still, a dephlegmator provided with conduits for the separate flow of vapors and residuum therethrough in one direction and of crude material therethrough in the opposite direction, flow conductors connecting the vapor, residuum and crude material conduits respectively of said dephlegmator and condenser, a pipe for conducting residuum from said still to the residuum conduit of said dephlegmator, and a pipe constituting a conduit for the vapor from the still to the dephlegmator and for the crude material and reflux from the dephlegmator to the still.
12. In an oil cracking system of hydrocarbon distillation, the combination of a tank for containing residuum under pressure, a still having a residuum conduit extending therethrough and communicating with said residuum tank, a dephlegmator provided with conduits for the separate flow of vapors and residuum therethrough in one direction and of the crude material therethrough in the opposite direction, a condenser provided with conduits for the separate flow of

- vapors and residuum therethrough in one direction and of the crude material therethrough in the opposite direction, flow conductors connecting the vapor, residuum and 5 crude material conduits respectively of said dephlegmator and condenser, a pipe for conducting residuum from the residuum conduit of said still to the residuum conduit of said dephlegmator, and a pipe surrounding 10 said residuum pipe and constituting a conduit for the vapor from the still to the dephlegmator and for the crude material and reflux from the dephlegmator to the still.
13. In a gravity flow cracking system of 15 hydrocarbon distillation, the combination of a still, a dephlegmator located on a higher level than said still, an oil tank located on a higher level than said dephlegmator, and a vapor condenser; pipes for conducting the crude material into said condenser, from 20 said condenser to said tank, and from said tank to said dephlegmator, means for conducting crude material from said dephlegmator to said still and vapors from said still to said dephlegmator, a pipe for conducting residuum from said still to said dephlegmator, pipes for conducting vapors and residuum from said dephlegmator to said condenser, and valves for regulating the 25 flow of the crude material into and from 30 said dephlegmator.

FRANCIS M. HESS.
